UNITED STATES PATENT OFFICE.

JAMES W. DINSMORE, OF LOOKEBA, OKLAHOMA.

COTTON-PICKER.

1,080,899.

Specification of Letters Patent.

Patented Dec. 9, 1913.

Application filed September 9, 1912. Serial No. 719,875.

To all whom it may concern:

Be it known that I, JAMES W. DINSMORE, a citizen of the United States, residing at Lookeba, in the county of Caddo and State of Oklahoma, have invented a new and useful Improvement in Cotton-Pickers, of which the following is a specification.

This invention relates to a cotton picker and relates to that type of pickers in which a motor driven suction fan is mounted upon a truck, wagon or any suitable type of movable platform and a flexible pipe has communication with the fan casing at one end and carries at its opposite end suitable means for drawing the cotton from the boll, and conveying the same to a suitable point of discharge mounted above said wagon, truck or platform.

This invention relates especially to the construction and arrangement of those parts adapted to collect the cotton from the boll, and to means for rapidly discharging the same at the discharge end, thereby maintaining a strong suction and giving freedom from clogging of any portion of the pipe.

In the accompanying drawings, Figure 1 is a side elevation of the device, parts being broken away. Fig. 2 is an enlarged longitudinal section through a collecting end of the suction tube. Fig. 3 is a section on the line 3-3 of Fig. 2. Fig. 4 is a section on the line 4-4 of Fig. 2. Fig. 5 is a vertical section. Fig. 6 is a section on the line 6-6 of Fig. 5. Fig. 7 is a horizontal section on the line 7-7 of Fig. 5.

In the drawings, 1 represents the top of a platform or the bed of a wagon or truck of any kind, and if desired the apparatus may be simply mounted upon the ordinary farm wagon or it may be placed upon an especially constructed truck as may be most convenient. Mounted upon this base 1 is an upright frame 2, upon which is mounted a motor 3 of the gasoline or any other preferred type. Mounted upon the upper portion of the frame 2 is a fan casing 4 and suitable pulleys 5 and 6 over which runs a belt 7 transmit power from the engine to a fan 9 arranged within the casing 4, the fan 9 and pulley 6 being both fixed upon a common shaft 8. In advance of the fan casing is arranged vertically a suction chamber 10, which communicates with the fan casing through a horizontal branch 11, a screen 12 being placed at the front entrance to said branch, thereby preventing cotton from be-

ing carried through the branch 11 into the casing 4. The suction chamber 10 has at its upper end a forwardly extending neck 13. To this neck is connected a suitable collecting tube consisting of a number of pipe sections 14 connected together by flexible joints 15. There may be any desired number of pipe sections and joints, according to the length it is desired to make the tube, and the various pipe sections may also be formed in any lengths convenient to handle. The lower end of the lowest pipe section 14 is rotatably connected to a collector 16. As shown in Fig. 4 this pipe section is provided with off-set circumferential slots 14^a and the collector, the inner end of which is cylindrical, is provided with exterior projections 16^a which work in the slots 14^a. The joints of the tube permit the same to be swung from side to side or up and down, and the connection just described between the collector 16 and the lowest pipe section of the tube permits turning of the collector with reference to said pipe, thus permitting the collector when thrust into the branches of the plant to be presented at practically any angle necessary in order to secure the cotton from the bolls. The mouth of the collector is enlarged and its front end is partially closed by an end plate 17, this plate being placed upon what may be conveniently termed the under or lower portion of the mouth. This acts as a shield and prevents leaves, pieces of boll and trash from being drawn into the collector. Arranged transversely in the upper portion of the mouth is a shaft 18 upon which are fixed two disks 19, one opposite each side wall of the collector. A wire screen 20 is secured upon said disks thereby forming a reticulated cylindrical drum.

It will of course be understood that the enlarged mouth portion of the collector is substantially rectangular in cross section. The drum 20 extends from side to side of the collector and projects slightly in advance of the same, the lower portion of the collector being cut-away at the front.

To drive the drum 1 run a belt 21 from the pulley 5, which may be a double pulley, and said belt runs over a double pulley 22 supported from the side of the suction chamber 10 and from the pulley 22 there runs a belt 23 which runs over pulley 24 fixed centrally upon a shaft 25, which shaft is arranged in suitable bearings beneath one of

the joints 15. The shaft 25 carries also a pulley 26 over which runs a belt 27 to a double pulley 28 carried by one of the joints 15. A belt 29 runs from the last mentioned 5 pulley to a pulley 30 arranged upon the outer end portion of the shaft 18.

To prevent the cotton winding about the drum 20 and insure its delivery into the tube I preferably arrange rollers 31 and 32 10 in the lower portion of the mouth and a belt 33 travels over said rollers and in close proximity to the wire drum 20. This belt will draw the cotton from said drum and start it inwardly through the collector. It 15 is of course understood that the suction fan is drawing a strong current of air through the collector and tube, said current passing through the drum 20. This air suction draws the cotton to the drum which immediately whirls it into the collector and upon the belt 33, and the air current carries it on to the suction chamber 10, where the cotton is deposited on the screen 12. The roller 32 carries upon the exterior of the 20 collector a pulley 33^a which is also driven by the belt 29.

While I have shown the rollers 31 and 32 and belt 33 as arranged for the purpose of preventing any winding of the cotton about 30 the drum, these parts are not considered absolutely essential as with a strong current of air there would be little danger of any cotton sticking to the drum after it had passed to the rear side of it, that is within 35 the collector. This belt 33 therefore is included simply as a precautionary measure, it may be discarded without appreciably affecting the operation of the device.

From the fan casing there extends downwardly an air discharge tube 35 which adjacent its lower end communicates with the lower end of the suction chamber 10. This tube therefore forms a discharge for both the cotton and the air from the collecting 45 tube.

In order to support the device suitable bars 36 are employed, and an overhead frame 37 is secured at its rear end to the upright frame 2 and at its forward end 50 supports a hanger 38 which forms a bearing for the shaft 25 and also for a bolt 39 upon which the joint 15, below which said shaft 25 is arranged, is supported.

In the vertical suction tube 10 I place 55 transversely across said tube and in alignment with the screen 12 a rotatable drum 40, which drum carries a plurality of flexible paddles 41, spaced apart so as not to interfere with the passage of air to the screen, 60 but at the same time arranged sufficiently

close together that they will wipe from the screen all cotton that might otherwise tend to stick to the screen. These paddles as shown are arranged in longitudinal rows along the drum and positively force the cotton into the lower portion of the tube 10. In this lower portion is arranged a second drum 42, provided with longitudinally extending blades 43, which extend entirely across the tube 10 and feed the cotton from 65 said tube into the discharge tube 35 and at the same time these blades act as valves preventing ingress of air from the discharge tube 35 outwardly into the tube 10. By means of this arrangement a very quick and 70 effective discharge of cotton is provided for without any danger of clogging the tube 10 either by the cotton collecting upon the screen 12 or by reason of an upward current of air in said tube which will of course tend 75 to retard downward movement of the cotton. The drum 42 is driven by the belt 21 and a belt 44 from said drum 42 drives the drum 40, as shown most clearly in Fig. 7.

What I claim is:

1. In a cotton picker, a flexible tube, means for creating a current of air therethrough, a collector, said collector being cylindrical at its inner end and rectangular at its outer end, the cylindrical end being 90 rotatably mounted in said flexible tube, and a rotatable reticulated drum arranged in the outer end of said collector, the air current passing into said collector through said drum.

2. In a cotton picker comprising a flexible tube, means for creating an air suction in said tube, a collector rotatably mounted upon the end of the tube, a rotatable reticulated drum carried in the outer end of the 100 collector, rollers transversely journaled in said collector and adjacent said drum and a belt running over said rollers.

3. A collector for cotton pickers consisting of a casing cylindrical at its rear end 105 and enlarged and rectangular at its front end, the front end being cut away upon its under side, and said cut-away portion being closed at the end, a rotatable reticulated drum mounted in the upper portion of the 110 collector, and projecting in advance of the closed end portion, and an endless belt arranged in the lower portion and adjacent said drum, said belt being adapted to travel longitudinally with respect to the collector, 115 as and for the purpose set forth.

JAMES W. DINSMORE.
